(57) **CLAIM**

The ornamental design for a control panel, as shown and described.

DESCRIPTION

FIG. 1 is a front elevational view of a control panel of the design according to the invention (a faceplate, which does not form part of the invention, is shown in phantom);
FIG. 2 is a top plan view of the control panel of FIG. 1 (a faceplate, which does not form part of the invention, is shown in phantom);
FIG. 3 is a bottom plan view of the control panel of FIG. 1 (a faceplate, which does not form part of the invention, is shown in phantom);
FIG. 4 is a left side elevational view of the control panel of FIG. 1 (a faceplate, which does not form part of the invention, is shown in phantom);
FIG. 5 is a right side elevational view of the control panel of FIG. 1 (a faceplate, which does not form part of the invention, is shown in phantom); and,

FIG. 6 is an isometric projection of the control panel of FIG. 1 (a faceplate, which does not form part of the invention, is shown in phantom).
The rear part of the control panel of FIG. 1 does not constitute part of the invention and, therefore has been omitted from the drawings.
